UNITED STATES PATENT OFFICE.

JOHN W. GINTER, OF EAU GALLIE, FLORIDA.

AUTOMATIC COMPRESSING-TANK.

1,323,854.

Specification of Letters Patent.

Patented Dec. 2, 1919.

Application filed May 14, 1918. Serial No. 234,440.

To all whom it may concern:

Be it known that I, JOHN W. GINTER, a citizen of the United States, residing at Eau Gallie, in the county of Brevard and State 5 of Florida, have invented new and useful Improvements in Automatic Compressing-Tanks, of which the following is a specification.

This invention relates to air compressors.

10 It is the object of this invention to utilize the surplus water from Artesian wells, springs, or other sources which is ordinarily wasted, as a means for compressing air so that the same may be used as motor power 15 for driving machinery, etc.

I attain this object, and others which will appear as the nature of the invention is more fully disclosed, by a construction, combination and operative arrangement of parts, 20 a simple and satisfactory embodiment of which being illustrated by the drawings.

In the drawings,

Figure 1 is a perspective view of the improvement.

25 Fig. 2 is a vertical longitudinal sectional view through the same, the tank being filled with water and exhausting the same as well as ejecting the compressed air therefrom.

Fig. 3 is a transverse sectional view approximately on the line 3—3 of Fig. 2.

30 Fig. 4 is a perspective view of the valve box which also provides the water inlet and outlet.

Figs. 5 and 6 illustrate details.

35 Fig. 7 is a detail elevation of the valve 44.

Fig. 8 is a sectional view through the said valve.

In carrying out my improvement I employ a closed cylindrical tank 10, of a desired size and capacity. Beneath the tank is a base 11, the same preferably comprising a wooden structure including sides 12 and ends 13 connecting the sides. The ends may be in the nature of spaced beams, and the sides 40 45 50 have their edges, beyond the center of the said sides beveled downwardly to one of the ends of the base, the inclined edges of the said sides being indicated by the numerals 14. Thus, it will be seen, the base provides a straight upper portion for the major portion of its length and an inclined portion for the minor part of its length.

For distinction I will refer to the elevated end of the base 11 as the front thereof, and 55 one of the connecting beams for the front is wider than the remainder, the said wid-

ened beam, being indicated by the numeral 15 and being let in the corners of the sides 12. The beam 15 has its central portion concaved as at 16 to provide a rest for the tank 10, when the said tank is in one position on the base.

The tank has secured thereon a frame, preferably constructed of metal and comprising sides 17, which are preferably of a skeleton form and connecting members in

the nature of plates 18 for the said sides. By reference to the drawings it will be noted that the frame is arranged nearer one end of the tank than the other end, so that one end of the said frame is disposed a considerable distance away from the end of the tank which rests on the beam 15.

Arched plates 19 are secured to the sides 17 of the supporting frame and are arranged around the bottom of the tank 10, the end arched members 19 resting and being secured, if desired, upon the plates 18, but the center members

19 are in the nature of segments and are braced and held against the sides of the tank by suitable plates 20 connected to the side members of the frame. Between the brace members 19, and upon the bottom of the tank 10 is secured a substantially rectangular box 21. This box, of course, has

its upper face arched or concaved, the said upper face being in the nature of a plate which is bolted or otherwise secured to the tank to provide a water tight joint between the box and the tank. The top plate of the

box is provided with two spaced parallel openings receiving valve seats 21 and 22, the said valve seats also entering the bottom of the tank 10 and providing communications between the box and the tank.

Below the valve seats 21 and 22 the box is provided with openings which are closed by plugs 24, and these plugs are only removed when access is to be obtained to the valves on the seats or for the adjustment of the seats.

In addition to these openings the box 21, upon one of its ends is provided with a plurality of additional openings which are preferably threaded and which are closed by plugs 25.

The sides of the box 21, adjacent to the end thereof provided with plugs 25 has alining round openings 26 surrounded by outstanding bosses 27, and threadedly engaging with the bosses are stuffing boxes 28 which also provide bearings for the water inlet pipe 29 and the water outlet pipe 30. The

5 pipes 29 and 30 pass through suitable bearing openings 31 in depending means 32 on the sides 17 of the supporting frame for the tank 10, and it will thus be noted that the pipes 29 and 30 provide pivots for the frame and for the tank. The pipe 29 is connected with the source of water supply and the pipe 30 may lead to any place where water is needed for any purpose, it being understood 10 that the water employed has a constant flow.

15 On the end of the pipe 29 in the box 21 is adjustably secured an arm 33, and likewise on the end of the pipe 30 in the box 21 is secured a similar arm 34. Both of these arms, adjacent their outer ends are provided with elongated slots and with elongated transverse openings communicating with the slots. The slots of each of the arms receive 20 a valve stem, the stem 35 in the slot of the arm 33 being connected with the intake valve 36 for the tank 10, and the stem 37 in the slot of the arm 34 being secured to the outlet valve 38 for the said tank 10. The 25 valve 36 opens inwardly of the box 21, the valve 37 opening outwardly of the box and inwardly of the tank.

30 The air line pipe is indicated by the numeral 39, the same communicating with the tank 10 adjacent to what I will term the front end thereof, said end, for distinction being indicated by the numeral 40. The pipe 39 is extended over the tank a distance greater than half of the length of the tank 35 and is provided with a round or bent portion 41 which is continued downwardly approximately in a line with the center of the supporting frame for the tank. The air pipe is then extended outwardly, as indicated by 40 the numeral 42, and this extension has arranged therein a check valve 43, permitting the air to flow outwardly through the pipe, but preventing the same returning through the pipe into the tank. In addition to 45 the valve 43, the vertical leg or pipe 38 has arranged thereon a valve 44, the casing of which being provided with a comparatively small inlet, and the stem of the valve has secured thereto a handle 45 which has its 50 free end loosely connected, as at 46 to a rod or bar 47 that is pivoted as at 48 to one of the sides 12 of the base 11.

55 On one or both of the sides 17 of the tank frame I arrange a rack bar or bars 49 upon which is suspended a yoke member 50 carrying a weight 51. The weight may be adjusted longitudinally of the frame on the rack bars and the said weight is designed to normally tilt the end of the tank upon 60 which it is arranged before sufficient water enters the tank to balance the same and to throw the inward end of the tank downward bringing the said tank to substantially horizontal position.

65 When the tank is arranged at an inclina-

tion the inlet valve 36 is unseated while the outlet valve 38 is seated. The stems 35 and 37 of the respective valves 36 and 38 are permitted a limited movement through the slots in the arms 33 and 34, but are connected 70 with the said arms by pins 52 passing through the elongated slots in the sides of the arms. When the tank is in its inclined position the water flowing through the pipe 29 enters the box 21, flowing therefrom into 75 the tank through the valve seat 22. As the tank fills the air will, of course, be compressed therein. When a pre-determined quantity of water flows in the tank (such quantity being regulated by the adjustment 80 of the weights 51) to overbalance the weights 51 the tank will swing to its horizontal position, seating the valve 36 and unseating the valve 38. This permits the water flowing through the opening 23 providing the 85 seat for the valve 38 and finding an outlet through the pipe 30. During the compression of the air by the inflow of water, such compressed air will find an outlet through the pipe 39 and is held against re- 90 entrance by check valve 43. When the tank is swung to its horizontal position the rod 47 acting on the pivot 46 of the valve 45, opens the said valve permitting air to enter through the valve and flowing through the 95 pipe 39 into the cylindrical tank 10.

95 The device is entirely automatic in action, the construction is simple as few parts are employed and none of which are liable to become disassembled, worn or broken, and it is believed that the advantages of the implement will be apparent without further detailed description.

Having thus described the invention what I claim is:

100 1. In combination, a lined water inlet and outlet pipes, a box journaled on the ends thereof, a tank secured to the box, adjustable weighted means arranged adjacent one end of the tank to tilt said tank, an air outlet pipe for the tank, a check valve therein, a second valve also arranged in said pipe, a water inlet and a water outlet valve between the box and tank, arms supported on the pipes and loosely receiving the stems of the 110 said valves whereby to hold the inlet valve open and the outlet valve closed when the tank is tilted, and also whereby to hold the inlet valve closed and the outlet open when a volume of water enters the tank sufficient 115 to overbalance the weighted means connected with the tank, and means for operating the second mentioned valve in the air pipe.

120 2. In a device for the purpose set forth, the combination with a base having a straight upper surface for the major portion of its length and an inclined surface therebeyond, a frame on the base, a tank for the frame, an inlet water pipe and an alined outlet water pipe arranged transversely of 125

the base at the juncture of the inclined and straight portions thereof and said pipes providing trunnions for the frame, a box secured to the bottom of the tank and receiving the ends of the said pipes, adjustable weights carried by the frame whereby to tilt the latter, the tank and box, an air pipe connected with the tank and having a check valve adjacent its outer end, an air inlet 10 valve in the air pipe, a handle therefor, a rod pivotally connected to the base and handle, a water inlet and a water outlet valve between the box and tank, arms ad-

justably secured on the ends of the respective inlet and outlet water pipes and loosely 15 supporting said valves, whereby to retain the inlet valve in open position and the outlet valve in a closed position when the tank is tilted, and also whereby to retain the outlet valve in an open position and the 20 inlet valve in a closed position when water has entered the tank in a sufficient quantity to overbalance the weighted means on the frame.

In testimony whereof I affix my signature. 25
JOHN W. GINTER.
